FOREIGN PATENT DOCUMENTS

CN 304397828 * 12/2017

Primary Examiner — Marissa J Cash*Assistant Examiner* — Altaira J Swangin(74) *Attorney, Agent, or Firm* — Yancy IP Law, PLLC(57) **CLAIM**

The ornamental design for a seat cushion for automobiles, as shown.

DESCRIPTION

FIG. 1 is a perspective view of the seat cushion for automobiles;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines, showing the circular details of FIGS. 1-7, depict portions of the seat cushion for automobiles, which form no part of the claimed design.

1 Claim, 7 Drawing Sheets(56)
